BUFFING WHEEL AND PROCESS OF MAKING
SAME

Russell A. Goodman, Cleveland, Ohio

Application March 14, 1936, Serial No. 68,912

1 Claim. (Cl. 51—193)

The present invention relates to the manufacture of buffing wheels such as used in buffing, polishing and coloring articles, and has as its object a new and improved method of making buffs and also an improved construction of the buff.

The usual type of buff is made from a plurality of plies of cloth which are laid upon one another with the threads running in varied directions and from which are cut circular blanks with a central shaft opening. These blanks are sewed, usually with a coarse spiral stitch, and are then ready to be mounted as units in a complete buffing wheel.

This method of making buffs is expensive and wasteful, both in the manufacture of the buff and also in operation. One of the main objections to this form of buff is that only a portion of the wheel can be used and the center is waste which has a small salvage value. In the use of buffing wheels, the speed of rotation is very high and as the buff wears away the surface speed is reduced to a point when it is no longer profitable to use it. To avoid this, the wheel is discarded when it is partially worn away, with the consequent loss of the center.

Other methods of making circular buffs have been proposed and some have gone into limited use. The method most commonly used is that which has been described, as it has heretofore been considered the most economical and efficient method.

The present invention has for its object a method of making a buff which will obviate the loss of material and will give a buff in which substantially all of the cloth may be usefully employed. It is a further object to devise a method of making buffs by which waste will be obviated in the manufacture of the wheel.

The accompanying drawings illustrate the method which has been found to be the most satisfactory for the purposes specified, and while the drawings and description are fully detailed in order to explain the best known method and the preferred construction, it will be understood that the same are subject to modification and improvement within the scope of the invention.

In the drawings:

Fig. 1 represents a plurality of layers of cloth laid up for cutting and illustrating a method of cutting the material;

Fig. 2 is a section on the line 2—2 of Fig. 1;

Figs. 3 and 4 are views illustrating the blocks or blanks which are cut from the original cloth, showing two methods of stitching;

Fig. 5 is a buff wheel made up from the blanks

illustrating the method by which the ring is first made roughly and then cut to form;

Fig. 6 shows a cross-section of a unit illustrating a method of clamping the ring to a holder;

Fig. 7 is a detail on the line 7—7 of Fig. 5; 5

Fig. 8 is a complete wheel;

Fig. 9 is a modified form of assembly by which the excessive thickness at the seams is avoided; and

Fig. 10 is an edge view of the device shown in 10 Fig. 9.

In the manufacture of the improved buffs, a plurality of plies of material, usually cotton cloth, are laid up in a long strip on a table or bench. In laying the material, the pieces composing the layers are usually placed in such manner that the threads in the several layers are at angles to each other. Any number of plies 1 may be laid up, the drawings illustrating twelve plies merely by way of illustration. 20

In the generally accepted method of manufacture, the material is now cut into roughly circular disks or blanks in which a central shaft opening is cut. This method is wasteful of material and labor. By my process, the plies are 15 cut into sector shaped blocks, preferably of general trapezoidal or keystone shape, along the lines 2 and 3 in the manner illustrated in Figure 1. By arranging the blocks alternately as shown, the waste is minimized. The size and shape of 25 the blocks 4 are determined by the size of the finished wheel or ring and the size of the opening which is to be left in the center. The illustration of the cuts in Figure 1 is merely to show one manner of cutting as the arrangement may 30 be changed and the number of blocks will vary with the size and dimensions of the completed ring.

The blocks 4 are preferably sewed at this time, either longitudinally as shown at 5 in Figure 3 40 or transversely as shown at 6 in Figure 4. The requisite number of blocks are then assembled into polygonal form with the inclined edges in contact. If the edges are overlapped as shown in Figure 5, the overlapping edges can be sewed 45 as shown at 8 in Figure 7. After the ring of blocks is assembled its outer edge is trimmed to circular form along the line 9 and any suitable form of clamp or holder is attached to the center. A metal crimping ring 10 is shown for the purpose, but this is only illustrative. 50

By this method of procedure, it is possible to construct a ring-shaped buffing wheel with a large central opening without undue waste of material. The ring so secured is operable with- 55

out the usual waste for it is possible to so dimension the parts that when the wheel shall have worn down to its limit of usefulness, only a small ring of fabric will be left. In addition, the buff wheel will be cooler than the ordinary type with a small shaft opening. In a buff wheel of say 14 inches in outside diameter, it is possible to have a full 6-inch opening at the center. These figures are given by way of example only.

10 A number of these buff units, which are indicated by the numeral 12, are usually mounted upon a shaft 13, as shown in Figure 8, any suitable form of chuck being employed for this purpose. In this view the wheel is broken away to show the spacing of the disk units about the shaft. The side plates 15 may be apertured to permit the circulation of air through the center of the wheel.

15 In order to avoid the thick overlap shown in Figure 7, where the blocks of full thickness are spliced, it is possible to make the individual blocks somewhat thinner and to stagger the seams as shown in Figures 9 and 10. This system may be extended to any desired extent to reduce the over-

laps accordingly. These views also illustrate an optional form of sewing in which the entire disk is given the usual spiral sewing. If desired outer plies 16 may be added to either form of buff section to cover the surfaces of the section.

5 It is obvious that modifications and changes may be made in the procedure of manufacture and the construction of the finished wheel, the invention being characterized by the fact that the buff wheel units are made from substantially 10 trapezoidal or keystone shaped blocks assembled in ring form with the large central opening giving maximum use of the fabric and also the additional cooling effect.

15 What is claimed is:

A ring-shaped buff wheel having a large central opening substantially equivalent to the waste area at the center of a standard buff wheel, said ring being composed of a plurality of trapezoidal blocks of multi-ply fabric sewed together and 20 assembled with their inclined edges in overlapped sewed relation and with their smaller parallel sides defining the large central opening.

RUSSELL A. GOODMAN.
